UNITED STATES PATENT OFFICE.

STEPHEN W. BALDWIN, OF NEW YORK, AND WILLIAM A. SWEET, OF SYRACUSE, NEW YORK.

RAILWAY-TIE.

SPECIFICATION forming part of Letters Patent No. 535,155, dated March 5, 1895.

Application filed April 21, 1894. Serial No. 508,417. (No model.)

To all whom it may concern:

Be it known that we, STEPHEN W. BALDWIN, of New York, in the county of New York, and WILLIAM A. SWEET, of Syracuse, in the county 5 of Onondaga, in the State of New York, have invented new and useful Improvements in Railway-Ties, of which the following, taken in connection with the accompanying drawings, is a full, clear, and exact description.

10 Our invention relates to metallic railway ties, and means, appliances and mechanisms for connecting or securing the rails thereto and securing it in the road bed.

The object of our invention is to produce 15 a metallic railway tie, in which the body is composed of sections secured together by transverse plates; in which each section is constructed of two or more bars of T-shaped iron or steel, or of other rolled shape; in which 20 the transverse connecting plates constitute chairs upon which the rails lie; in which abutments, or an abutment plate is connected to the tie, and grip plates bear at one end upon said abutments and at the other upon 25 the rail flanges to secure each rail upon its chair plate; in which each tie is provided with a vertical transverse anchor, or anchors, which prevents the tie from shifting longitudinally; and in which the longitudinal sections 30 are separated from each other, thereby creating a tamping-slot between them.

Our invention consists in the several novel features of construction and operation hereinafter described and which are specifically 35 set forth in the claims hereunto annexed. It is constructed as follows, reference being had to the accompanying drawings, in which—

Figure 1, is a top plan of a tie and parts of two rails. Fig. 2, is a front elevation thereof. 40 Fig. 3, is an end elevation of a tie, and part of a rail thereon in side elevation. Fig. 4, is a top plan of the tie. Fig. 5, is a vertical sectional elevation of part of the tie, rail thereon and means for connecting the tie sections, 45 and securing the rail thereon. Fig. 6, is a side elevation and a top plan of the abutment plate, detached. Fig. 7, shows two perspectives of grip bars, showing slight differences in construction. Fig. 8, is a front elevation 50 of one style of anchor, detached, before it is bent. Fig. 9, is a like view of another an-

chor, slotted to receive the webs of the tie sections. Fig. 10, is a side elevation of the anchor showing the arms bent laterally with a single angle or curve. Fig. 11, is a like view 55 showing the arms bent over with two angles, or curves. Fig. 12, is a top plan of part of a tie, showing partly in full and partly in dotted lines an anchor of the style shown in Fig. 9, secured to the tie sections. Fig. 13, is a side 60 elevation of an abutment like that shown in Fig. 6, and having one of the grip-plates integral with the body. Fig. 14, is a side elevation of an anchor and a brace connected thereto.

—A— is the tie, comprising a body consisting of two or more longitudinal sections —a—, of any suitable metal, each being of T-shape, or of other rolled shape, in cross section and inverted so that the longitudinal 70 web is on the under side, or buried in the earth, while the space —b— between them is the “tamping” space. Chair plates —c— are secured to and connect said sections, and the heads, or the outer projection of the bolts or rivets —c'— form a channel in which the flange —d'— of the rail —d— lies, said heads bearing laterally against it.

A plate —e— having its ends upturned to create the abutments —e'— is inserted under 80 each of said chairs and between said sections, and —h—, —h— are grip plates, at one end engaging with said abutments, and at the other bearing upon the flange of the rail, —h'— being a bolt inserted through each of 85 the grip plates, chairs and plate —e— on each side of the rail, by which said parts are adjustably secured together and the rail is secured upon the tie.

To prevent the longitudinal shifting or 90 movement of the tie, where necessary, as upon curves, an anchor —k— is provided, comprising a plate having arms —k'— which are bent over in opposite directions by a single angle or curve, as shown in Fig. 10, or by two 95 angles or curves as in Fig. 11, the latter being the stronger method, and less liable to fracture under strain.

In Fig. 9, the anchor is shown as provided with vertical slots —m— creating two arms 100 at each end of the anchor, the arms of each pair being bent in opposite directions, and

the webs of said sections fitting into said slots, whereby the area of the anchor is largely increased, as well as its strength, against lateral strains, to prevent the longitudinal shifting of the tie. These anchors are secured by bolts or rivets through the flange of each section, and stand vertically transverse thereto.

5 The sections can be produced by cutting the heads off from old railroad rails, and rolling the web and flange down to the desired thickness, and cutting to length.

10 In the drawings the tie sections are shown as T-shaped in cross section, but we do not limit ourselves to that form, inasmuch as the principle of our invention will enable us to use many different types or styles of rolled shapes for such sections in constructing ties in sections which are spaced apart and connected or secured together by chairs, connections or anchors in separate pieces, or combined to create either a combined chair or anchor or a combined connection and anchor.

15 What we claim as our invention, and desire to secure by Letters Patent, is—

20 1. A railroad tie comprising two or more parallel rolled-shape sections, flat chairs secured thereon, grip-plates inserted undersaid chairs and provided with end abutments projecting above them, clips engaging with said 25 abutments and with the flanges of the rails lying upon said chairs and bolts through them and the chairs and grip-plates in combination with a rail.

30 2. A railroad tie comprising two or more parallel rolled-shape sections, chair plates se-

cured thereon transversely, grip-plates secured to said chairs and having upturned ends projecting above said chairs, clips engaging with the rail flanges and provided with tongues engaging with the grip-plates and means to adjustably secure them, in combination with a rail lying upon said chairs.

35 3. The combination with a rail of a tie consisting of T-shaped sections, rail chairs connecting them, an anchor fitting over the ribs of the sections and having oppositely bent arms secured to the sections on the opposite sides of said ribs and extending below them, abutment plates secured to said chairs, grip-plates engaging with the abutments and with the rail flanges, and bridging over the spaces between said abutments and said flanges and means to secure said grip-plates to the chairs and abutment plates.

40 4. The combination with a rail, of a sectional tie having a tamping slot between the sections, a chair connecting the sections and engaging with the rail, an abutment plate, grip plates engaging with the abutments and with the rail flanges and bridging over the spaces between them, and means to secure said plates in position.

45 In witness whereof we have hereunto set our hands this 9th day of January, 1894.

STEPHEN W. BALDWIN.
WM. A. SWEET.
